(57) **CLAIM**

The ornamental design for the protective guard for optics, as shown and described.

DESCRIPTION

FIG. 1 is a front view of the protective guard for optics; FIG. 2 is a front-elevation view of FIG. 1, the right side being a mirror image;

FIG. 3 is a side view of FIG. 1, the right side being a mirror image; and,

FIG. 4 is a rear-elevation view of FIG. 1.

This embodiment protects the optics from damage for firearms.
